UNITED STATES PATENT OFFICE.

OVERTON WINSTON, OF MINNEAPOLIS, MINNESOTA.

BULB-STENCILING DEVICE.

1,258,293.

Specification of Letters Patent.

Patented Mar. 5, 1918.

Application filed December 16, 1916. Serial No. 137,439.

To all whom it may concern:

Be it known that I, OVERTON WINSTON, a citizen of the United States, residing at Minneapolis, in the county of Hennepin and 5 State of Minnesota, have invented certain new and useful Improvements in Bulb-Stenciling Devices; and I do hereby declare the following to be a full, clear, and exact description of the invention, such as will 10 enable others skilled in the art to which it appertains to make and use the same.

My invention has for its object to provide a bulb stenciling device for use in applying wax coating to the main body portion of 15 an electric light bulb to thereby prepare the same for application of frosted surfaces, and is in the nature of a modification of or improvement on the so-called stenciling device disclosed and claimed in my prior application, S. N. 135,580, filed of date, December 7th, 1916, and entitled "Bulb stenciling device."

Generally stated, the invention consists of the novel devices and combinations of 25 devices hereinafter described and defined in the claims.

In the accompanying drawings which illustrate the invention, like characters indicate like parts throughout the several views.

30 Referring to the drawings:

Figure 1 is a side elevation showing the stenciling device and an electric light bulb held thereby;

Fig. 2 is an enlarged view partly in side 35 elevation and partly in vertical section, and with some parts broken away, showing the device in the same position as illustrated in Fig. 1;

Fig. 3 is a section on the line 3—3 of 40 Fig. 2;

Fig. 4 is a section on the line 4—4 of Fig. 2;

Fig. 5 is a view corresponding to Fig. 2, but showing the bulb holding socket still 45 closed on the bulb shank, but moved to carry the bulb away from the stencil blocks;

Fig. 6 is a very much enlarged section on line 6—6 of Fig. 7, showing means for anchoring the bulb ejecting spring to one of 50 the jaws of the bulb socket;

Fig. 7 is a front elevation of the parts shown in Fig. 6, some parts being broken away;

Fig. 8 is a fragmentary view of certain of 55 the parts shown in Fig. 7; and

Fig. 9 is a view corresponding to Fig. 5,

but showing the socket of the stenciling device moved to an extreme open position.

The stenciling device comprises a suitable handle 11 having a curved stencil bar or 60 extension 12 to which one or more stencil blocks are applied. As shown, there are two of these stencil blocks 13 and 14, each of which is fitted within and held by a flanged metal holder 15 shown as provided 65 with a threaded stem 16 projected through a perforation in the stencil bar 12 and clamped thereto, by a nut 17. The stencil blocks 13 and 14 are formed with concave faces so that they engage the globe *a* of the 70 light bulb, only at their marginal edges. These stencil blocks are advisably made of rubber but may be made of other slightly elastic or flexible material such, for example, as leather or compositions of leather, 75 rubber and the like.

The shank *b* of the light bulb has the customary diametrically projecting lock lugs *c*. As shown, the said bulb is of the two-filament type, being provided with an 80 axial filament *a*¹ and a vertically offset filament *a*².

The shank of the light bulb is arranged to be clamped in a divided socket carried by a so-called clamping lever that is pivoted to the handle. This so-called clamping lever 18 has a hub 19, at one end that is located in a recess or bifurcation 20 of the handle 11, and is loosely pivoted thereto, on a pin 21 with freedom for slight lateral 90 and endwise wabbling motion.

The bulb socket is made up of two jaws or members 22 and 23, the former of which is formed integral with a projecting arm of the clamping lever 18. The jaw 23, at its 95 rear end, has a hinge lug that works in a recess of the jaw 22 and is pivotally connected thereto by a pin 24. The socket jaws 22 and 23, at their outer ends, are approximately semi-cylindrical, and they are 100 formed with internal stop shoulders 25 against which the lock lugs *c* of the bulb socket are adapted to be pressed by a coiled spring 26. This coiled spring 26, as will hereinafter be noted, serves also as a bulb 105 ejector. Its outer end presses against the inner end of the shank of the bulb, and its inner end is anchored to the base of the socket jaw 23, preferably, by means of an anchoring plate 27 detachably secured in a 110 recess of the said jaw 23 by a screw 28 (see particularly Figs. 6, 7 and 8). By refer-

- ence particularly to Figs. 7 and 8, it will be noted that the extreme inner end of the spring 26 is bent inward at 26^a to fit a lock notch 26^b in the base of the said jaw 23. 5 The bearing on the base of the jaw 23 against which the inner end of the spring 26 is anchored, is at an oblique angle to the axis of the closed socket (see particularly Figs. 2 and 5) and is at such angle thereto, 10 that when the socket is completely open, as shown in Fig. 9, the axis of the spring will be midway between the two jaws 22 and 23, and hence, will exert a force on the proper line for ejecting the bulb.
- 15 The relatively movable bulb clamping jaw 23 works between laterally spaced cheek plates 27 and is provided with a cam pin 28 that projects at both ends, and at its ends, works in cam slots 29 of said plates. 20 Approximately the front half portion of these cam slots 29 are concentric to the axis of the pivot 4, but the rear half is eccentric to said axis and operates as hereinafter described.
- A leaf spring 30 fixed at one end to the 25 lever 18 presses against the jaw 23 and yieldingly forces the same toward the coöperating jaw 22. A leaf spring 31 is anchored at one end to the shank of the handle 11 and yieldingly presses the free end of lever 18 30 outward, and hence, tends to move the two jaws 22 and 23 toward the stencil block 13.
- Pivoted on the shank over the handle 11 is a spring pressed latch 32 that is engageable 35 with lock notch 33 on the hub of the lever 18, when said lever and the jaws 22 and 23 are moved in the position shown in Fig. 5.
- The numeral 34 indicates a peek hole in the bar 12.
- Operation.*
- 40 The operation of the stenciling device, briefly described, is substantially as follows: The shank of the light bulb will be inserted into the socket while the socket jaws 45 22 and 23 are opened up, as shown in Fig. 9, and the said socket jaws will be closed on the bulb socket when the parts are moved from the position shown in Fig. 9 into the position shown in Fig. 5. This closing movement of the socket jaws is produced by the cam action of the eccentric portions of the cam slots 29 acting on the ends of the cam pin 28. When the parts are moved from the position shown in Fig. 5 to the position 55 shown in Figs. 1 and 2, the light bulb will be firmly held by the socket and its globe will be moved into tight contact with the stencil blocks 13 and 14. The light bulb may be rotated on its axis so as to set the filaments a^1 and a^2 in proper position, in 60 respect to the frosted surfaces which are to be produced in the zones covered by the stencil blocks. The operator, looking through peek hole 34, can accurately determine when the filaments are properly positioned.

When the light bulb is held in position, as above described, it may be dipped into hot paraffin, or other wax, thereby covering the entire surface of the globe, except those places or zones that are covered by the so- 70 called stencil blocks 13 and 14.

To remove the bulb from the socket, it is only necessary to press the lever 18 and thereby move the same and the socket into the position shown in Fig. 9. In this position, the socket is opened up and the spring 26 will then automatically eject the bulb. Under the movement of the lever 18 from the position shown in Figs. 1 and 2, into the position shown in Fig. 5, the socket 80 jaws remain closed upon the shank of the light bulb and the latch 32 will hold the said parts against return movements.

Obviously, it is the movement of the parts from the position shown in Fig. 5 into the 85 position shown in Fig. 9, that moves the cam pin 28 in eccentric portions of the cam slots 29 and causes the opening of the bulb holding socket.

After the wax has been applied to the 90 globe of the bulb, as described, it may be dipped in an acid which will have a chemical action on the glass and which will produce the frosted effect on the surfaces or zones not covered by the wax, and thereafter, the wax can be removed by dipping the bulb in boiling water.

What I claim is:

1. A stenciling device comprising a handle having an extension provided with a 100 stencil block, a lever pivoted to said handle, a two-part bulb socket connected to said lever, and means for opening and closing said socket by movements of said lever.

2. A stenciling device comprising a handle having an extension provided with a stencil block, a lever pivoted to said handle, a two-part bulb socket member connected to said lever, and means for opening and closing said socket by movements of said 110 lever, said socket member having internal shoulders engageable with the lock lugs of a bulb shank to hold the same with freedom for rotary adjustments.

3. A stenciling device comprising a handle having an extension provided with a stencil block, a lever pivoted to said handle, a two-part bulb socket member connected to said lever, and means for opening and closing said socket, by movements of said lever, 120 said socket member having internal shoulders engageable with the lock lugs of a bulb shank to hold the same with freedom for rotary adjustments, the extension bar of said handle having a peek hole for determining 125 the proper rotary adjustment of the bulb.

4. A stenciling device comprising a handle having an extension provided with a stencil block, a lever pivoted to said handle, a two-part bulb socket member connected to 130

said lever, means for opening and closing said socket by movements of said lever, and an ejector spring within said socket serving to automatically eject the bulb from the 5 open socket.

5. In a stenciling device, the combination with a handle having an extension provided with a stencil block, a lever pivoted to said handle, a light bulb socket comprising two 10 members, one rigidly secured to said lever and the other pivoted thereto, a cam secured to said handle, and a cam projection on the movable socket member engageable with said cam and coöperating therewith to close the socket under outward movement of said lever, and to open said socket under inward movement of said lever.

6. In a stenciling device, the combination with a handle having an extension provided 20 with a stencil block, a lever pivoted to said handle, a light bulb socket comprising two members, one rigidly secured to said lever and the other pivoted thereto, a cam secured to said handle, and a cam projection on the 25 movable socket member engageable with said cam and coöperating therewith to close the socket under outward movement of said lever, and to open said socket under inward movement of said lever, the inner portion of 30 said cam being concentric to the pivotal connection between said lever and handle, and the outer portion thereof being eccentric thereto.

7. In a stenciling device, the combination with a handle having an extension provided 35 with a stencil block, a lever pivoted to said handle, a light bulb socket comprising two members, one rigidly secured to said lever and the other pivoted thereto, a cam secured to said handle, a cam projection on the 40 movable socket member engageable with said cam and coöperating therewith to close the socket under outward movement of said lever, and to open said socket 45 under inward movement of said lever, the inner portion of said cam being concentric to the pivotal connection between said lever and handle, the outer portion thereof, being eccentric thereto, a spring yieldingly 50 pressing said lever outward, and a latch for securing said lever in an intermediate position with the socket moved outward but still closed.

8. In a stenciling device, the combination with a handle having an extension provided 55 with a stencil block, a lever pivoted to said handle, a light bulb socket comprising two members, one rigidly secured to said lever and the other pivoted thereto, a cam secured to said handle, a cam projection on the 60 movable socket member engageable with said cam and coöperating therewith to close the socket under outward movement of said lever, and to open said socket under inward 65 movement of said lever, the inner portion of

said cam being concentric to the pivotal connection between said lever and handle, and the outer portion thereof being eccentric thereto, a spring yieldingly pressing said lever outward, a latch for securing said lever 70 in an intermediate position with the socket moved outward but still closed, and a spring carried by said lever and yieldingly pressing the movable socket member toward its closed position. 75

9. In a stenciling device, the combination with a handle having an extension provided with a stencil block, a lever pivoted to said handle, a light bulb socket comprising two members, one rigidly secured to said lever 80 and the other pivoted thereto, a cam secured to said handle, a cam projection on the movable socket member engageable with said cam and coöperating therewith to close the socket under outward movement of said lever, and to open said socket under inward movement of said lever and a coiled spring within said socket anchored to one of the 85 socket members and tending to eject the bulb from said socket. 90

10. In a stenciling device, the combination with a handle having an extension provided with a stencil block, a lever pivoted to said handle, a light bulb socket comprising two members, one rigidly secured to said lever 95 and the other pivoted thereto, a cam secured to said handle, a cam projection on the movable socket member engageable with said cam and coöperating therewith to close the socket under outward movement of said lever, and to open said socket under inward movement of said lever, a coiled spring within said socket anchored to one of the socket members and tending to eject the bulb from said socket, a spring re-acting against said 100 handle and lever and tending to force the latter away from the former, and a spring reacting against said lever and movable socket member. 105

11. A stenciling device comprising a handle having an extension provided with a stencil block, a lever pivoted to said handle, a two-part bulb socket connected to said lever, means for opening and closing said socket by movements of said lever, a spring 110 tending to move the lever away from said handle, and a latch for holding said lever against movement under force of said spring. 115

12. In a stenciling device, a combination 120 with a handle having an extension bar provided with a stencil block and formed with laterally spaced cheek plates having cam grooves therein, of a spring pressed lever pivoted to said handle, and a bulb socket 125 comprising two jaw members, one fixed to said lever and the other pivoted thereto, the said pivoted member having cam projections engaging said cam grooves of said cheek plates, substantially as described. 130

13. In a stenciling device, the combination with a handle having an extension bar provided with a stencil block and formed with laterally spaced cheek plates having cam grooves therein, of a spring pressed lever pivoted to said handle, and a bulb socket comprising two jaw members, one fixed to said lever and the other pivoted thereto, the said pivoted member having cam projections 10 engaging said cam grooves of said cheek plates, said cam grooves having portions concentric to and other portions eccentric to the pivotal connections between said lever and handle.
14. A stenciling device comprising a han-

dle having an extension, a stencil block holder detachably secured to said extension, a stencil block detachably and replaceably held in said holder, a lever pivoted to said handle, and a light bulb socket carried by 20 said lever and adapted to hold a light bulb with its globe positioned against said stencil block.

In testimony whereof I affix my signature in presence of two witnesses.

OVERTON WINSTON.
